UNITED STATES PATENT OFFICE.

SIDNEY GEORGE BROWN, OF LONDON, ENGLAND.

SIPHON-RECORDER.

1,080,412.

Specification of Letters Patent.

Patented Dec. 2, 1913.

Application filed February 6, 1912. Serial No. 675,797.

To all whom it may concern:

Be it known that I, SIDNEY GEORGE BROWN, a subject of the King of Great Britain, residing at 4 Great Winchester street, in the city and county of London, England, have invented certain new and useful Improvements Relating to Siphon-Recorders, of which the following is a specification.

10 This invention relates to siphon recorders, the chief object being to use a short siphon tube and to mount the tube and control its movements in such a way that its weight or inertia can be considerably reduced, and in 15 consequence a greater speed of recording attained than has hitherto been practicable, with the present form of long siphon tube.

According to the present invention the siphon tube and the parts coöperating with 20 it are so constructed and arranged that the length of tube employed is considerably shorter than is customary, and the inertia of the tube and the degree of control necessary for it are reduced. The said tube is so 25 mounted with respect to the ink supply outlet that the ink inlet end of the tube is co-axial with the axis about which the oscillatory movements of the tube take place, or, even if the said tube occupies a position in 30 which its inlet end is out of alinement with the axis of oscillation, there will be no tendency for the tube to be moved by the surface tension of the ink. The ink may be supplied to the siphon tube in any con- 35 venient way, but I prefer to employ an ink reservoir with an outlet extending to a point below the siphon tube carrier. In the case of the siphon tube being mounted with its inlet end co-axial with the axis of oscillation, the ink supply outlet may consist of a 40 tube with a hole bored centrally with respect to the aforesaid axis of oscillation of the siphon tube. The size of the hole in this ink supply tube is such that the ink will 45 be prevented from overflowing by reason of the surface tension of the exposed surface of the ink in the hole; of course, it will, however, flow along the siphon tube in proportion to the demand. A siphon tube mounted 50 as above described need be only about half an inch long instead of the usual length of about two and a half inches. In the case of the siphon tube being mounted with its inlet end slightly out of alinement with the 55 axis of oscillation, it will be understood that the edge of the ink reservoir or of its supply

tube must necessarily be near to the inlet end of the siphon tube. Hence the surface tension of the ink will have a tendency to drag the inlet end of the siphon tube into 60 contact with the edge of the said reservoir or supply tube, unless special precautions are taken to obviate this tendency. With this object I make the edge of the ink reservoir or supply tube adjacent to the inlet 65 end of the siphon tube circular and concentric with the path of movement of the said inlet end, so that the surface tension of the ink has no greater tendency to move the siphon tube in one direction than in the op- 70 posite direction.

The siphon tube carrier is made light but rigid, and may conveniently consist of a small plate or bar of aluminium, suitably stiffened if necessary by one or more ribs or 75 corrugations; it may be held in a horizontal position by the usual suspension fibers, wires, or strips, but since the ink inlet end of the siphon tube, and hence also the ink supply, is immediately under or only slightly 80 to one side of the said carrier, the lower suspension fiber, wire, or strip, is not directly attached to this carrier but is attached to two vertical silk threads which extend downwardly from two points on the sides of the 85 carrier or from two depending lugs thereon.

Any appropriate means may be employed to impart to the siphon tube the customary continuous vibration. The means I prefer to adopt comprise a tuning fork kept in a 90 vibratory condition by an electromagnet, the vibrations of one limb of the fork being transmitted to the siphon tube. This transmission may be effected either through a resilient member attached to some part of 95 the siphon-tube mounting, for instance one of the suspension fibers, or through a frame supporting not only the siphon tube but also its suspension fibers, wires or strips; in the latter case the said frame is firmly attached 100 to the limb of the tuning fork and the whole frame and all it carries vibrate together.

One or each suspension fiber, wire, or strip, instead of being fixed directly to a suitable part of the frame, may be passed 105 over one or more corners of the frame and then be secured to a spring situated beyond the corners. In this way the steadiness of the suspension fibers, wires, or strips, is insured.

In order to transmit the oscillating movements of the usual coil of the recorder to

the siphon tube, the siphon tube carrier may be connected to the coil, or to a magnifying arm carried thereon, by a silk transmitting thread. It is preferable however for the transmitting thread to be fastened by shellac or otherwise to one of the vertical silk threads hereinbefore referred to as depending from the siphon tube carrier; in this way the twisting or bending that would otherwise occur at the point of connection of the transmitting thread with the siphon tube carrier is avoided and is taken up by a slight twisting of the vertical thread about its own axis. It will be understood that owing to the inertia of the tube being lessened by shortening it, the degree of control required to hold it in position is lessened, and the power required to move it is correspondingly reduced; hence the speed of signaling is increased.

In order that the invention may be clearly understood and readily carried into effect, I will now describe the same more fully with reference to the accompanying drawings in which:—

Figure 1 is a plan of a complete apparatus adapted to work in accordance with the invention. Fig. 2 is an end elevation, and Fig. 3 a side elevation of the same. Fig. 4 is a detached view of a modified arrangement for supplying the ink to the siphon tube. Fig. 5 is a diagrammatic view of a modified manner of arranging the oscillating coil and siphon tube. Fig. 6 is a side elevation and Fig. 7 a cross section showing a further modification of the suspension device for the siphon tube and carrier.

Like letters of reference indicate similar parts in all the figures.

A is a hard steel permanent magnet core, and A' A' are windings to convert the permanent magnet into an electromagnet when necessary; A², A² are its adjustable pole pieces, and between them is suspended the oscillating coil B. This coil B carries a magnifying arm B' to which is attached the transmitting thread B² at an intermediate point in the length of the latter; the ends of the thread B² are secured to two blade springs, one of which B³ (Fig. 1) is mounted horizontally and protected by a guard piece B⁴, while the other B⁵ (Fig. 3) is mounted vertically and protected by a hood B⁶. Thumb screws are provided to adjust these springs, and hence also the tension in the transmitting thread B². At another intermediate point in its length, the transmitting thread B² is attached, preferably by shellac, to one of two vertical silk threads C² depending from the carrier C' of the siphon tube C. The carrier C' is a small thin plate of aluminum and the vertical silk threads extend between this plate and a similar one vertically below it. The ends of the threads C² are brought together

beyond the plates and secured to the suspension wires C³. The lower suspension wire is passed around two corners of the lower arm d of the vibratory frame D, and is attached to a coiled spring D', while the upper suspension wire is attached to a rod D² which is vertically adjustable between the portions of the split upper arm d' of the said frame.

The frame D is kept in vibration by means of an electromagnet E the armature of which is shaped like a tuning fork, as shown by E^x. The frame D is attached to one limb of the fork and the other limb is balanced by weights E' to increase the steadiness of the vibrations of the frame.

E² is the contact at which the circuit of the winding of the electromagnet E is rapidly made and broken.

The strip of paper F on which the records are made is shown in dotted lines in Fig. 3. It passes under the pivoted weight F', around the guide F², and over a guide roller F³, and thence over the recording drum G from which it is drawn by the paper feeding mechanism H. The passage of the paper over a drum or equivalent curved surface at the place where the recording is done is a generally known arrangement, but it is especially beneficial in the case of my unusually short siphon tube owing to its having the effect of eliminating curvature in the recording lines upon the paper. The marking or outlet end of the siphon tube C bears upon the paper on the drum G and the inlet end dips into the ink as will now be described.

In the arrangement shown in Figs. 1-3 the inlet end of the siphon tube lies on the common axis of oscillation of the upper and lower aluminium plates C', C', and the vertical threads C² C². The said inlet end dips centrally into a hole bored vertically on the upper side of a tube J' leading from the ink reservoir J. In order that this reservoir may be removed at any time and replaced to exactly the same position, I have provided a curved guide J² with a groove J³ in it for engagement with a lug on the reservoir J, so that to return the reservoir to its plate at any time it is merely turned angularly as far as the groove J³ will allow, and is then raised vertically and clamped by the screw J⁴.

In the arrangement shown in Fig. 4 the ink inlet end of the siphon tube C is out of alignment with its axis of oscillation but the edge of the ink reservoir or supply tube is correspondingly curved, so that the surface tension effects of the ink upon the inlet end of the siphon tube are negligible.

Reverting to the apparatus shown in Figs. 1, 2 and 3, it may be mentioned that the spindle of the recording drum G is slightly eccentric with respect to the bearing that

supports it, so that by turning the drum and spindle about their bearing the surface of the drum can be adjusted in position relatively to the marking end of the siphon tube C. In order to counterbalance the weight of the siphon tube C a small weight may if desired be fixed to the aluminium plate C' to which the said siphon tube is also attached. G' is a shield situated between the recording drum and the siphon tube.

In a modified arrangement designed to dispense with the usual one or more transmitting threads and to effect a more direct and positive transmission of the coil movements, the siphon tube C may be mounted on the same axis as the oscillating coil by the above mentioned suspension wires, as seen diagrammatically in Fig. 5. To compensate for the necessarily increased angular movement of the coil, the latter may be reduced in diameter and weight. I prefer to use a coil considerably narrower than the usual siphon recorder coils, and in order to make this coil as light as possible I may employ very fine enamel-covered copper or aluminium wire. The usual permanent or electromagnet will of course be suitably arranged to accord with such a positioning of the coil. This arrangement may be adopted whether the inlet end of the siphon tube is co-axial with or displaced from the axis about which the tube oscillates.

Instead of supporting the siphon carrier in a frame D carried by one limb of the tuning fork, I may connect the suspension fibers or wires C², C³, of the siphon carrier to flat springs c¹⁰, c²⁰ (see Figs. 6 and 7) the upper one of which forms part of an adjustable stop device c¹¹ and the lower one is attached to the bottom limb c²⁰ of the tuning fork and is adapted to strike against a stop c²¹ situated near its free end; thus although the spring and suspension device are suddenly arrested in their downward movement by this stop, the limb c²⁰ of the tuning fork can continue to move downward. To prevent the spring c²⁰ from bouncing when it strikes the stop it may be provided with a dash pot or similar arrangement; in the example shown I have provided two small vessels c²² containing heavy cylinder oil, one being situated at each side of the spring. The spring is provided with a cross wire c²³ preferably consisting of steel wire of about $\frac{3}{8}$ ths of an inch thick and suitably bent to permit of the free end c^{23x}, c^{23x} entering the said vessels c²² (see Fig. 7). I find it advantageous to arrange the suspension fibers or wires C², the stop c²¹ and the device c²², c²³, at the free end of the spring c²⁰ and in the same vertical plane. The lower suspension fibers C³ may be tied in a small hole in the spring c²⁰ and a zero adjustment dispensed with.

The fibers C³, C³, might however be provided with small hooks for enabling them to be easily connected with the springs c¹⁰, c²⁰.

In addition to maintaining the usual continuous vibration of the siphon tube, the flow of ink may be further facilitated by electrifying it. The necessary voltage may be generated in any convenient way, as, for example, by placing a transformer winding E over the magnet winding E and by completing the circuit of this winding through the drum G and ink reservoir J, as shown in Fig. 6.

What I claim and desire to secure by Letters Patent of the United States is:—

1. In siphon recording apparatus, a siphon tube only about one half of an inch in length, fibers suspending the tube with capability of oscillation about a vertical axis, means controlling the oscillatory recording movements of the tube, said means being proportionate to the small weight and inertia of the tube incidental to its short length, and siphon-tube-ink-supplying means preserving constant surface tension conditions between the ink surface and the ink inlet of the tube notwithstanding the oscillatory recording movements of the said tube.

2. In siphon recording apparatus, a siphon tube, and means supporting the tube with its ink inlet end co-axial with the axis about which the oscillatory recording movements of the tube take place.

3. In siphon recording apparatus, a siphon tube, a siphon tube carrier, fibers suspending the said tube and carrier with freedom to oscillate about the inlet end of the siphon tube, and means supplying ink to the said inlet end.

4. In siphon recording apparatus, a light narrow rigid plate, a similar plate situated vertically below it, a pair of parallel fibers attached to and extending between the pairs of plates, upper and lower suspension fibers supporting and controlling the aforesaid plates and pair of parallel fibers, a siphon tube supported by one of the aforesaid rigid plates with its inlet end co-axial with the suspension fibers, and means to which the remote ends of the suspension fibers are attached.

5. In siphon recording apparatus, a light narrow rigid plate, a similar plate situated vertically below it, a pair of parallel fibers attached to and extending between the pair of plates, upper and lower suspension fibers supporting and controlling the aforesaid plates and pair of parallel fibers, a siphon tube supported by one of the aforesaid rigid plates with its inlet end co-axial with the suspension fibers, means to which the remote ends of the suspension fibers are attached, and means for keeping the aforesaid means in constant vibration.

6. In siphon recording apparatus, a light

narrow rigid plate, a pair of fibers attached to and extending from the plate, upper and lower suspension fibers supporting and controlling the aforesaid plate and pair of fibers, a siphon tube supported by the aforesaid rigid plate with its inlet co-axial with the suspension fibers, supports to which the remote ends of the suspension fibers are attached, and electro-magnetic means for keeping one of the supports in constant vibration.

7. In siphon recording apparatus, a light narrow rigid plate, a pair of fibers attached to and extending from the plate, upper and lower suspension fibers supporting and controlling the aforesaid plate and pair of fibers, a siphon tube supported by the aforesaid rigid plate with its inlet end co-axial with the suspension fibers, blade springs to which the remote ends of the suspension fibers are attached, a tuning fork to one limb of which one of the blade springs is secured, and electromagnetic means for keeping the said limb in constant vibration.

25 8. In siphon recording apparatus, a light narrow rigid plate, a similar plate situated vertically below it, a pair of parallel fibers attached to and extending between the pair of plates, upper and lower suspension fibers supporting and controlling the aforesaid plates and pair of parallel fibers, a siphon tube supported by one of the aforesaid rigid plates with its inlet end co-axial with the suspension fibers, a frame to which the remote ends of the suspension fibers are attached, and a spring interposed in the attachment of one of the suspension fibers to the frame.

9. In siphon recording apparatus, a light narrow rigid plate, a pair of fibers attached to and extending from the plate, upper and lower suspension fibers supporting and controlling the aforesaid plate and pair of fibers, a siphon tube supported by the afore-

said rigid plate with its inlet end co-axial 45 with the suspension fibers, means to which the remote ends of the suspension fibers are attached, an oscillating coil responsive to the line currents, and means for transmitting the movements of the coil to the siphon tube 50 by way of one of the above mentioned pair of fibers.

10. In siphon recording apparatus, a light narrow rigid plate, a pair of fibers attached to and extending from the plate, upper and lower suspension fibers supporting and controlling the aforesaid plate and pair of fibers, a siphon tube supported by the aforesaid rigid plate with its ink inlet end co-axial with the suspension fibers, means to 55 which the remote ends of the suspension fibers are attached, electromagnetic means for transmitting continuous vibrations to the siphon tube through the aforesaid means, and means associated with the aforesaid 60 electromagnetic means and deriving electric energy therefrom for electrifying the ink supplied to the siphon tube.

11. In siphon recording apparatus, the combination with a siphon tube mounted 70 with its ink inlet end co-axial with the axis about which the oscillatory recording movements of the tube take place, of an ink reservoir and a pipe extending therefrom to a point beneath the inlet end of the siphon 75 tube and having an ink outlet hole on its upper side immediately beneath the inlet end of the siphon tube, the size of the hole being so small as to prevent the overflow through it of ink from the reservoir owing to the 80 surface tension of the ink exposed at the hole.

In testimony whereof I affix my signature in presence of two witnesses.

SIDNEY GEORGE BROWN.
